Eugene R. Salay, 1417 Juneau Court, Tucker, Ga. 30084,
and Longin A. Orzechowski, 974 Rosedale Road NE,
Atlanta, Ga. 30306

Filed Nov. 21, 1966, Ser. No. 4,766

Term of patent 14 years

(Cl. D71—1)

FIG. 1 is a side elevational view of the invention;
FIG. 2 is a top plan view of the invention; and,
FIG. 3 is a front elevational view of the invention.

In view of the prior art, the characteristic features of our design reside in the overall appearance resultant from the shape and placement of the canopy element in association with the conventional hull structure, as shown.

We claim:

The ornamental design for a boat, substantially as shown and described.
